UNITED STATES PATENT OFFICE

163,700

ROOM-CORNER LOUD-SPEAKER

Paul W. Klipsch, Hope, Ark.

Application March 9, 1950, Serial No. 8,408

Term of patent 14 years

(Cl. D26—14)

To all whom it may concern:

Be it known that I, Paul W. Klipsch, a citizen of the United States of America, residing at Hope, Hempstead County, State of Arkansas, have invented a new, original, and ornamental Design for a Room-Corner Loud-Speaker, of which the following is a specification, reference being made to the accompanying drawing, forming a part thereof.

Fig. 1 presents a perspective view of the front, top and right side of the room-corner loud-speaker, showing my new design;

Fig. 2 is a right side elevation; and

Fig. 3 is a top plan view.

I claim:

The ornamental design for a room-corner loud-speaker, substantially as shown.

PAUL W. KLIPSCH,
